United States Patent Office

Des. 193,146
Patented July 3, 1962

193,146

EDUCATIONAL GAME BOARD

Richard L. Riddle, 3405 Potomac St., and LeRoy S. Moskowitz, 3710 Coy St., both of Winston-Salem, N.C.

Filed Oct. 31, 1961, Ser. No. 67,326

Term of patent 3½ years

(Cl. D34—5)

The FIGURE is a perspective view of the educational game board, showing our new design.

The dominant features of our design reside in those portions shown in solid lines.

We claim:

The ornamental design for an educational game board substantially as shown and described.
